SPINDLE AND BOBBIN CONSTRUCTION

**Rexford P. Bennett, Honesdale, Pa., assignor to
Clover Leaf Manufacturing Co., a corporation
of Pennsylvania**

Application March 8, 1941, Serial No. 382,278

9 Claims. (Cl. 242—46.2)

This invention relates to bobbins and spindles used in spinning machines for doubling and twisting operations and more particularly to improved bobbin constructions and means for driving same.

Considerable difficulty has been experienced heretofore in the spinning and twisting of yarns at high speeds in that the bobbins have a tendency to vibrate, wobble and climb the blade of the spindle. This is particularly true in recent years with the demand for higher and higher speeds of operation. In spinning synthetic yarns, for example, it is now customary to use speeds of 12,000 to 14,000 R. P. M. and in some cases as high as 16,000 R. P. M. In spinning silks, still higher speeds have been attempted. These extremely high speeds of operation increase the tendency of the bobbin to vibrate and pound on the spindle regardless of how fine a tolerance is provided between the size of the bore and the size of the spindle. While the bores of bobbins have heretofore been designed to closely fit the blades of spindles with a view to eliminating vibration and wobble at high speeds, nevertheless vibrations of minute amplitude are created which cause the bores of the bobbins to be pounded out to an oversized condition within a relatively short period of time. This oversized condition of the bore of a bobbin permits the bobbin to wobble and puts increased strain on the machine. It also increases the tendency of the bobbin to climb or bob up and down on the spindle and thereby increases the danger that it will fly off.

According to my invention, I provide a bobbin with a bushing of a novel construction presenting spindle-engaging surfaces backed by a resilient material interposed between the bobbin proper and the bearing surface of the bushing whereby vibrations that might otherwise be imparted by the spindle blade when operating at high speeds are absorbed without the occurrence of the objectionable wobbling and pounding effects heretofore experienced.

Another feature of the invention resides in the provision of a spindle having a bobbin rest provided with an annularly arranged inclined surface and a bobbin with a base having a similarly inclined surface adapted to engage the inclined surface of the bobbin rest in driving relation, the engagement being such that the weight of the bobbin maintains the surfaces in effective driving relation, even at extremely high operating speeds while at the same time an operator may easily release, remove and replace the bobbin.

while the bobbin is still travelling at considerable speed.

A further feature of the invention is the provision of a sturdy and relatively simple bobbin construction having a resilient bushing disposed at one end thereof to absorb vibrations between the bobbin and the spindle, and means at the opposite end of the bobbin to hold the same in close driving relation with respect to the spindle without binding thereon.

A still further feature of the invention is the provision of a bobbin having a bushing adapted to fit closely the base of the spindle blade and another bushing backed by resilient material adapted to engage a portion of the blade spaced from the base thereof whereby relative movements between the bushings and the blade at high operating speeds are substantially eliminated.

Additional features of the invention will become apparent upon consideration of the following detailed description to be read in connection with the accompanying drawing, in which:

Figure 1 is a fragmentary plan view of the upper end of one form of a bobbin embodying the novel bushing construction of the present invention;

Figure 2 is a vertical sectional view of the bobbin taken along line 2—2 of Figure 1 and showing the bobbin mounted on a spindle for a thread doubling operation;

Figure 3 is a bottom plan view of the bobbin as viewed along the line 3—3 of Figure 2;

Figure 4 is a vertical sectional view of the bobbin mounted on a spindle for a thread twisting operation;

Figure 5 is a view in vertical section with parts broken away showing a bobbin and a spindle construction embodying a modified form of the driving means of the present invention; and

Fig. 6 is a view in vertical section with parts broken away showing a bobbin and a spindle construction embodying another modified form of the driving means of the present invention.

Referring to Figures 1, 2 and 3 of the drawing, a spindle 10 is shown provided with the usual whorl 12, a bobbin rest 14 and a blade 16. The rest 14 is provided with pins 18 adapted to be received in recesses in the end of a bobbin and to provide positive driving engagement with a bobbin placed upon the spindle. The blade 16 is enlarged at 20 to center and closely receive the lower portion of a bobbin bore.

The bobbin of the present construction is shown as comprising a body member 22 made of wood or other suitable relatively light weight

material to which end pieces 24 and 25 are attached. These may be made of laminated fiber, metal or other suitable material. The body member 22 is provided with a bore 26 which is slightly enlarged at both ends to receive bushings 28 and 34. The bushing 28 at the lower end of the bobbin is made of metal or other wear resisting material and is adapted to fit the enlarged portion 20 of the spindle blade with only slight clearance. A clearance of not more than .002" is recommended.

The bushing 34 at the opposite end of the bobbin is made up of an outer tubular member 33, an inner tubular member 36 made of brass or other wear resisting and low friction material, and a resilient filler material 38 interposed therebetween. The interposed material 38 may consist of rubber or other material having suitable resilient characteristics, the material being vulcanized to the members 33 and 36 or held therebetween by other suitable means. The outer end of the tubular member 33 is shown as flared at 40 to assist in holding the bushing in position on the body 22. The end piece 24 is provided with a central opening in which a protective cup-shaped element 42 is held with the inner edge thereof against the flared portion 40.

Adjacent the bushing 28 and attached on the outer or lower side of the end piece 25 is a base member 30 made of a phenolic condensation product, rubber, cork or other material suitable for friction driving purposes as hereinafter more fully described. As shown in Fig. 1, the base 30 is provided with openings 32 to receive the pins 18 and in this way establishes a positive driving connection with the spindle. It is preferred to provide the bobbin with the base member 30 and to provide the openings 32 therein, since by so doing the bobbin may be positively driven from the spindle as in a doubling operation or it may be used with the modified types of bobbin rest shown in Figs. 4 and 5 in twisting operations. However, it will be understood that the advantages derived from the use of my novel bushing construction may be realized, particularly in doubling operations, by omitting the base member 30 and forming the pin-receiving recesses or openings 32 in the end piece 25a, as shown, by way of example, in Fig. 6, wherein like numerals refer to corresponding elements shown in Fig. 2.

In using the bobbin for a doubling operation the bobbin is first placed upon the spindle 10 with the bushing 28 fitting rather closely about the enlarged portion 20 and the bushing 34 closely engaging the upper end of the blade 16. The bushing 34 with its loading of rubber or other resilient material 38 acts to absorb vibration in conjunction with the bushing 28 and thereby overcome any tendency of the bobbin to wobble and as a consequence there is little tendency for the bore opening to wear and become enlarged. In addition, the close fitting resilient engagement of the upper bushing 34 with the spindle blade serves to minimize any tendency of the bobbin to "walk" or raise up on the spindle blade even when the bobbin is being driven or rotated at high speeds.

When a sufficiently large bundle of doubled thread has been spun onto the bobbin, the bobbin is removed from the spindle 10 and may then be placed upon a spindle adapted to perform a twisting operation and usually operated at a relatively high speed as compared with doubling. In Fig. 4 there is shown a spindle 50 adapted for

twisting operations and provided with a novel bobbin rest and driving connection for coacting with the bobbin hereinbefore described. This spindle is provided with a bobbin rest 52 which 5 has a peripheral flange 54. The inner surface 56 of the flange 54 is inclined slightly with respect to the axis of the spindle. The base 30 of the bobbin is shaped as a frustum of a cone thereby presenting an outer peripheral surface 57 which is inclined to the axis of the bobbin. When the bobbin is placed upon the spindle 50, the inclined surfaces 56 and 57 engage and when the bobbin is being driven it serves to establish a friction engagement which acts to overcome any 10 tendency of the bobbin to move up the spindle blade and fly off.

It is important that the inclination of the surfaces 56 and 57 shall be so selected as to insure satisfactory performance. The optimum inclination may vary somewhat with the friction characteristics and other properties of the material used in forming the surfaces 56 and 57. When using a Bakelite resin, I find that the inclination, for best performance, should be between 15 about 6 to 8 degrees with the vertical. An inclination of about 7 degrees has been found to give satisfactory operation at extremely high operating speeds. With the inclination of the surfaces 56 and 57 at about 7 degrees the bobbin, even when manually urged upwardly from the bobbin rest while travelling at extremely high speeds, promptly returns to the driving surface 56 and assumes a steady and smooth operation. With this inclination for the friction driving 20 surfaces the bobbin does not bob up and down on the spindle or produce a wobbling effect. If the inclination is much less than 6 degrees the bobbin has a tendency to bind and become difficult to remove from the spindle. If the inclination of the surfaces 56 and 57 are made more than 8 or 9 degrees, the bobbin has a tendency to bob upwardly on the spindle.

The above described advantages of the annularly disposed inclined driving surfaces of the 25 bobbin and spindle are greatly enhanced by the rubber-loaded bushing 34. Since the bushing 34 at the top of the bobbin provides a resilient absorbing medium for vibration produced at high operating speeds, the effect thereof is to dampen 30 vibratory tendencies of the bobbin and thereby maintain the same properly centered with the friction surface 57 in substantially even contact with the surface 56.

Referring to Figure 5 of the drawing, a modified arrangement of inclined driving surfaces is 35 provided between the spindle 60 and the bobbin base 62. In this form the outer surface 64 of the peripheral flange 66 of the bobbin rest 67 is inclined to the axis of the spindle. The base 60 62 of the bobbin is provided with a peripheral flange 68, the inner surface 70 of which is inclined to the axis of the bobbin. These inclined surfaces are of substantially identical inclination and when engaged provide a close lateral fitting 40 relation as well as an excellent friction driving engagement.

By locating the driving surfaces of both forms (Figs. 1-4 and Fig. 5) outwardly a distance from the axis of the spindle an increased friction 45 driving area is provided which substantially eliminates slippage and greatly increases stability of the bobbin for high speed operations.

While I have shown and described two different embodiments of the invention, I recognize 50 that many additional modifications and varia-

tions of my invention are possible without departing from the spirit thereof. It should, therefore, be understood that the forms of the invention herein illustrated and described are intended to be illustrative only and not as limiting the scope thereof.

I claim:

1. A bobbin for use in doubling and twisting yarn adapted to be mounted on the blade and bobbin rest of a spindle for operation at high speeds, said bobbin having a bore to receive the blade and a base adapted to be received on the bobbin rest for driving engagement therewith, a bushing at the end of the bore adjacent said base to engage the portion of the blade adjacent the bobbin rest and a second bushing adjacent the opposite end of said bobbin, said second bushing including a tubular metallic member adapted to closely receive a portion of said blade, said tubular member being spaced from the body of said bobbin by an annular body of a highly resilient material which acts as a cushion between said tubular member and the body of said bobbin throughout the length of said tubular member.

2. A bobbin for use in doubling and twisting yarn adapted to be mounted on the blade and bobbin rest of a spindle for operation at high speeds, said bobbin having a bore to receive the blade and a base having a vertically inclined surface disposed annularly adjacent the periphery thereof and adapted to be received in friction engagement with a similarly inclined surface on the bobbin rest whereby to establish a driving relation between said bobbin rest and said bobbin, and said bore being provided adjacent its outer end with a tubular metallic element backed throughout the length thereof by a resilient material and having an inner diameter such as to closely receive the upper portion of said blade.

3. A bobbin for use in doubling and twisting yarn comprising an elongated body having a bore lengthwise thereof and a bushing mounted therein adjacent the outer end of said bobbin including a pair of concentrically arranged spaced tubular elements and a highly resilient material disposed therebetween throughout the length thereof, and the inner of said tubular elements being made of a wear-resisting metal and having an inner diameter such as to closely receive the upper end of a spindle blade when the bobbin is mounted thereon.

4. A bobbin for use in doubling and twisting yarn comprising an elongated body having a bore lengthwise thereof, a bushing in one end of the body including a metallic, wear-resisting tubular element spaced from the wall of said bore and a highly resilient material disposed between the element and the wall of said bore and extending throughout the length of said element, and means at the opposite end of said body for establishing positive driving engagement with a driving means and for maintaining said bobbin positively centered with respect to the axis of rotation of said driving means.

5. In a spinning machine for doubling and twisting yarn, in combination, a spindle having a blade and a bobbin rest, the bobbin rest being provided with an annularly disposed vertically inclined surface, and a bobbin having a bore to receive said blade and a base adapted to be received on said rest with a portion thereof in engagement with said inclined surface, said inclined surface being at an angle between 6 and 9

degrees to the vertical, said bore being provided with a rubber loaded tubular metallic bushing disposed adjacent the outer end of said bobbin and having an inner diameter such as to closely receive an upper portion of a spindle blade when the bobbin is mounted thereon.

6. In a spinning machine for doubling and twisting yarn, in combination, a spindle having a blade and a bobbin rest, the bobbin rest being provided with an annularly disposed vertically inclined surface, and a bobbin having a bore to receive said blade, a base provided with an annularly disposed inclined surface adapted to be received in engaging relation with the inclined surface on said rest, said bore being provided with a rubber loaded tubular metallic bushing disposed adjacent the outer end of said bobbin and having an inner diameter such as to closely receive an upper portion of the spindle when the bobbin is mounted thereon and said vertically inclined surfaces being so adjusted as to inclination as to establish and maintain a friction driving engagement between said bobbin and the bobbin rest when the bobbin is driven at speeds attained in twisting operations and at the same time being so adjusted as to permit the driving engagement to be easily broken when the speed of the bobbin has been reduced.

7. In a spinning machine for doubling and twisting yarn, in combination, a spindle having a blade and a bobbin rest, the bobbin rest being provided with a peripheral flange with one side thereof inclined at an angle between 6 and 9 degrees to the vertical, and a bobbin having a bore to receive said blade and a base provided with an annularly disposed similarly inclined surface adapted to be received in engaging relation with the inclined surface of said flange, said bobbin having at the outer end of the bore thereof a tubular bushing composed of a hard, wear-resisting material and adapted to closely receive the upper end of the spindle blade, and said bushing further including an annular body of a highly resilient material extending throughout the length of the said tubular member and acting as a cushion between said bushing and the body of said bobbin.

8. In a spinning machine for doubling and twisting yarn, in combination, a spindle having a blade and a bobbin rest, the bobbin rest being provided with a peripheral flange with the inner surface thereof inclined at an angle between 6 and 9 degrees to the vertical, and a bobbin having a bore to receive said blade and a base of frusto-conical shape adapted to be received on said rest with the outer conical surface of said base in friction driving engagement with the similarly inclined inner annular surface of said flange, said bobbin having at the outer end of the bore thereof a tubular bushing composed of a hard, wear-resisting material and adapted to closely receive an upper end of the spindle blade, and said bushing further including an annular body of a highly resilient material extending throughout the length of the said tubular member and acting as a cushion between said bushing and the body of said bobbin.

9. In a spinning machine for doubling and twisting yarn, in combination, a spindle having a blade and a bobbin rest, the bobbin rest being provided with an annularly disposed vertically inclined surface, and a bobbin having a bore to receive said blade, a base provided with an annularly disposed inclined surface adapted to be received in engaging relation with the inclined sur-
